UNITED STATES PATENT OFFICE

1,969,603

ERASING SHIELD

Fred H. Gibson, Westwood, N. J.

Application October 19, 1933, Serial No. 694,295

5 Claims. (Cl. 120—41)

This invention relates to erasing shields and has for an object to provide a construction which will permit correct erasures to be made and at the same time prevent marking and off-
setting on the carbon sheets.

Another object of the present invention is to provide an erasing shield wherein there is provided an upper and lower member so formed that by grasping it with one hand the lower member may be slid between the top sheet and the back of the carbon sheet, while the upper member which is perforated is slid over the matter to be erased, whereby all parts of the typewritten sheet are protected except that which is to be acted upon by the eraser and at the same time the pressure on the eraser is not transmitted to the carbon sheet.

An additional object of the invention is to provide an erasing shield wherein an upper and a lower structure are provided and connected together in a manner presenting a pinching structure at one end, whereby when the erasing shield is in operative position one edge of the paper is pinched and the eraser shield is held against accidental shifting.

A still further object of the present invention is to provide an erasing shield for making erasures on typewritten sheets wherein an apertured slide is presented capable of ready movement across the sheet at any time while being held in line with the matter to be erased.

In the accompanying drawing—

Figure 1 is a perspective view of an embodiment of the invention shown in use;

Figure 2 is a top plan view of the shield shown in Figure 1, a portion being broken away for illustrating certain detailed features;

Figure 3 is a longitudinal sectional view through Figure 1 approximately on the line 3—3;

Figure 4 is a top plan view similar to Figure 2, but showing a slightly modified structure;

Figure 5 is a transverse sectional view through Figure 2 on the line 5—5, the same being on an enlarged scale;

Figure 6 is a view similar to Figure 5 but showing a modified construction of the invention;

Figure 7 is a fragmentary top plan view on a reduced scale showing one end of a slightly modified structure to that illustrated in Figure 2;

Figure 8 is a sectional view through Figure 7 on the line 8—8, the same being on an enlarged scale.

Referring to the accompanying drawing by numerals, 1 indicates a typewriter of any desired kind into which a number of sheets of papers 2, 3 and 4 are inserted. Between the sheets of paper sheets of carbon 5 and 6 are arranged. This structure is the usual structure now in common use where two carbon copies are to be made. During the typewriting operation it is not unusual for the operator to strike a wrong letter and when this occurs a correction must be made. Occasionally a wrong word is used or an incorrect spelling and when this occurs the word must be erased and the correct one substituted. To do this it has been the practice to use a shield held by hand for protecting all the typing except that to be erased. As the erasing requires some considerable pressure it is customary to place another sheet of paper or a blotter either in front or in back of one or both of the carbon sheets so that there will be no smearing or offsetting of the carbon. In the present instance the shield obviates the use of a blotter or other sheet material placed in front or back of the carbon sheets.

As illustrated in Figures 2 and 3 there is provided an upper plate 7 and a lower plate 8, said lower plate having a portion 9 extending beyond the upper plate as shown at the right in Figure 2. These plates are formed from a single sheet of material or, if desired, are rigidly secured together, though as illustrated in the drawing they are formed of the same sheet and bent at points 10 and 11 so that the portion 12 may act as a handle. The material of which the respective plates are made may be metal, celluloid or other comparatively stiff flexible substance.

As the upper and lower plates are connected together only at point 10, if the upper plate is grasped at points 13 and 14, as indicated by the hand in dotted lines in Figure 1, and then lifted, plate 8 will swing downwardly a short distance whereby the extension 9 may be inserted beneath sheet 2 and over the back of the carbon sheet 5. Preferably the device is forced over sheet 2 until it is somewhat pinched at point 15 where the plates 7 and 8 approach each other. This pinching action is only slight but it acts to hold the device in the proper place on sheet 2.

Plate 8 is preferably smooth and unperforated, though below points 13 and 14 it is provided with cutaway portions 16 and 17 whereby when the plate is grasped at the points 13 and 14 the fingers will not grasp plate 8. The upper

plate 7 is provided with a slot 18 extending from the handle 12 to near the opposite end, and in this slot a sliding plate 19 is positioned. Sliding plate 19 is preferably provided with two rows 5 of apertures in an irregular manner whereby an apertured erasing opening is presented for all contingencies. Plate 19 is slightly wider than the slot 18 so as to underlap the same, as indicated by the dotted lines in Figure 4. However, 10 this plate is formed with overlapping ears 21 which slide over the upper surface of plate 8, said sliding action being caused by the operator grasping the handle 22 and moving the sliding plate to the desired position. When the device 15 is applied as shown in Figure 1 none of the apertures 23 may be in the right position. Consequently the sliding plate may be moved by means of the handle 22 so that an aperture will be correctly positioned over the place to be erased. 20 If the erasure should be longer than the aperture used the sliding plate 19 may be shifted slightly so as to make the additional erasure. In connection with the sliding plate 19 it will be seen that in the structure shown in Figure 25 4 the sliding plate 19' is provided with only a single row of apertures 23'. When this is the case the entire device must be shifted upwardly or downwardly to secure a proper alignment, but in the preferred form if the lower line of 30 apertures are not properly set the upper one will fit or possibly one of the irregularly positioned openings. It will be understood that one, two or more rows of apertures may be provided without departing from the spirit of 35 the invention and that they may be arranged in various ways, though ordinarily two rows parallel to each other are provided, said rows being spaced apart equally to a single spacing in the typewriter. In addition, preferably some 40 transverse openings as, for instance, aperture 23'', are provided to take care of unusual contingencies.

The plates 7 and 8 are made of very thin material and the slide 19 is also made of very 45 thin material as shown in Figure 5. In Figure 6 a slightly modified structure is shown wherein the plate 7 is provided with longitudinally positioned raised portions 24, said raised portions permitting slideways or cavities for the sliding 50 plate 19, thus permitting the ears 21 to fit over the raised portions and the bottom of the plate 19 to be flush with the bottom of plate 7. After an erasure on the first sheet has been accomplished the same action is carried out for the 55 second and third sheets, and as the device may be readily slipped in place and slide 19 adjusted, quick erasures may be made without any danger of producing any offsets on the carbon.

60

65

70

75

As shown in Figures 7 and 8 a slightly modified structure is presented wherein the bottom plate 8' is the same as shown in Figures 2 and 3 but the top plate consists of side members or guides 25 and 26 which are U-shaped in cross section, as shown in Figure 8. By reason of this construction the slide 19 may move back and forth in a similar manner to that shown in Figure 2 and, in addition, may move so as to extend beyond the extension 9 so that any desired aperture 23 or 23'' may be used at the end or beyond the end of plate 8'. 80

I claim:—

1. An erasing shield comprising a pair of thin flexible plates connected together at one end, one of said plates having notches near the end where it is connected to the other plate whereby when said other plate is grasped adjacent said notches said notched plate will swing a short distance below the plate held by the hand, whereby the notched plate may be readily slipped beneath a sheet of paper, the plate grasped by the hand being formed with an opening for exposing the matter to be erased. 90

2. An erasing shield including a pair of thin flexible plates, said plates being superposed with one of the respective ends connected together permanently, one of said plates acting as a protecting plate and the other as a shield member, the plate acting as a shield member having a longitudinally positioned slot and a slide arranged in said slot. 95

3. An erasing shield including a bottom plate, a top plate having a slot extending longitudinally thereof, and an apertured slide arranged in said slot. 100

4. An erasing shield including a slotted plate, a slide arranged in the slot in said slotted plate, said slide having an apertured body with the edges underlapping said plate and ears overlapping the plate, a handle extending from one end of said slotted plate whereby the plate may be manipulated. 115

5. An erasure shield used in erasing matter from paper in typewriting machines, including a pair of thin flexible plates, said plates being superposed with one of the respective ends connected to the other, one of said plates being adapted to be inserted beneath the sheet of paper to be corrected on the typewriter, and the other above the sheet, the last mentioned plate being formed with a longitudinally positioned slot whereby the plate will be substantially rectangular, said upper plate being swingable in respect to the lower plate. 120
